UNITED STATES PATENT OFFICE

THEODORE BARBATO, OF UNION CITY, NEW JERSEY

SLAB CONSTRUCTION

Application filed June 6, 1927. Serial No. 196,697.

The invention relates to a slab construction for use in fire proof buildings having frames of structural steel or re-inforced concrete; and in buildings of wall-boarding design; and for use, in fact, in all types of building construction where fire-proof floors are desirable. More particularly, the invention relates to slab constructions of combined hollow tile and re-inforced concrete having a 10 cantilever action, and providing a flat ceiling, without intermediate beams, over long spans; and also providing a thin flooring, to permit of increased head-room or decreased height of building for saving of structural steel or 15 re-inforced concrete.

Hollow tile and concrete have heretofore been variously combined in flooring. In certain of such combinations, however, the tile has been used as a mere filler, with no 20 function as a compression member and no action as a cantilever; and this despite the fact that hard burnt clay has a compressive strength one and one half times that of concrete. In other cases the strength of the 25 tile has been recognized, and the tile so positioned in the concrete as to function in compression with the concrete. In instances such as the last, however, each tile has been separately embedded in and bonded on all 30 four sides by the concrete, and the concrete allowed to enter both ends of each tile, with the result that the concrete constitutes an excessive proportion of the slab, and the slab as a whole is of far greater weight than de- 35 sirable economy in the size of the floor supports would dictate. Furthermore, by reason of the excessive amount of concrete therein, such a slab in itself is much more expensive than would be the case were the area of tile 40 enlarged to a proper and attainable degree; and, due to its large area of concrete such a slab offers but a limited area of tile on which to plaster. Again, in structures in which 45 unset concrete is allowed to enter or close both ends of the hollow tile, water accumulat- ing within the tile, as the concrete sets, is shut off from the atmosphere, and proper drying of the structure is thus prevented.

An object of the present invention is a 50 combination tile and re-inforced concrete

slab in which the tile and concrete act both in compression and as a cantilever, and are so proportioned and arranged that the slab may have great strength in long-span structural framing, little weight, and a minimum 55 depth, be laid with rapidity by unskilled labor and when laid may quickly and thoroughly dry; and which, by reason of a relatively high proportion of tile, is largely of cheap and cheaply laid material offering an extensive 60 area of flat ceiling for plastering.

In a slab in which the re-inforced concrete is in two intersecting systems of elements or ribs, or otherwise, it is an object of the invention so to space these ribs that the apertures 65 or areas of the net or open work thereby formed, are of a size to accommodate tile-units, each composed, not of a single tile as heretofore, but of a plurality of tiles, preferably four in a two-way system, set against 70 each other so that by their bearing one on the other within the unit, and by their bearing on the concrete without the unit, they act as compression members; and so that by reason of the joints at the abutting faces of 75 the tiles, the interior of the tiles may be drained and dried with the setting of the concrete.

In the preferred form of the invention the tile units each comprise four tiles so set to one 80 another that one open end of each tile abuts the closed side wall of another tile; each side of the tile-unit thus presenting the side wall of one tile and the open end of another. In this construction, therefore, the concrete, 85 which forms the adjacent ribs of the network, (and which is poured or tamped into the spaces between the tile units after the latter have been positioned on flat building forms, in the squares or areas defined by the previously positioned re-inforcing rods), may protrude into but one open end of each tile, instead of into both ends of every tile, as heretofore. Each tile-unit as a whole may nevertheless be interlocked on each side, by 90 reason of such protrusions of concrete, with the adjacent re-inforced concrete ribs.

In a modified form of the invention the 95 four tiles of a tile-unit are arranged so that the closed side wall of one tile abuts the 100

closed side wall of another, and the other two tiles are similarly set to one another and placed end-on with respect to the first two. Here again, the concrete can enter only one open end of each tile.

5 In a further modification of the invention, the corners of the tiles are cut so that pockets are formed when the tiles are set together; these pockets having concrete tamped therein 10 to bond the end face of the side wall of one tile to that of another.

15 In one form of the invention a concrete surfacing over both the tiles and the concrete rib-elements, and unitary with the latter may also not only be unitary with the concrete in the aforesaid pockets, but may be tamped into any crevices between abutting tiles which arise from irregularities in the tile surfaces; thus assuring a full bearing of 20 one tile on another over the entire opposing surfaces of the tiles.

Other features of the invention will hereinafter appear in connection with the accompanying drawings, in which:

25 Fig. 1 is a top plan view of a portion of flooring embodying the invention.

Fig. 2 is an enlarged view in cross-section taken on the line 2—2 of Fig. 1.

30 Fig. 3 is a top plan view of a portion of flooring embodying a modified form of the invention.

Fig. 4 is a view in cross-section taken on the line 4—4 of Fig. 3.

35 Fig. 5 is a view in cross-section taken on the line 5—5 of Fig. 3.

Fig. 6 is a top plan view of a portion of flooring embodying a further modification of the invention.

40 Fig. 7 is a view in cross-section taken on the line 7—7 of Fig. 6.

Fig. 8 is a view in cross-section somewhat similar to that of Fig. 4 except that a top surfacing of concrete is shown over the tiles and unitary with the concrete filling between 45 the tile-groups.

Fig. 9 is a view in cross-section of a modified form of the invention in which the I beams of Fig. 2 are replaced by concrete beams.

50 Referring to the drawings, and more particularly to Figs. 1 and 2, there is shown a portion of flooring supported by piers or columns 10. Set upon these columns and extending from one to another of such columns are 55 I beams 11, set in concrete 12. The concrete haunches 12 are formed in the usual manner by pouring the concrete in suitable forms around the previously positioned I beams 11. Two systems of such beams extending at right-angles, one to the other, form the supports for the flooring.

60 The flooring or floor slabs, are made upon ordinary flat forms, (not shown), erected in a manner well known in the building trade. 65 In making the flooring or slab shown in Figs.

1 and 2, reinforcing steel bars 13 are laid in two systems at right angles one to the other, the bars of each system being spaced preferably 28" apart on centers. In the spaces or sections formed by bars 13 are assembled four pieces of 12" x 12" hollow tile, the depth of which depends on the size of the panel. As shown in Fig. 1, these four pieces are assembled to form one unit. The tiles are of the usual form, having side walls 14 and internal webs 15. The webs, with one another, and with the side walls, form cells 16 having open ends at each end of the tile. One open end of each of the four tiles in each unit of Fig. 1 bears against the closed side or wall of another of such tiles; so that there is on each side of each four-tile unit, the open end of one tile and the closed side or wall of another tile.

When these four-tile units, to the desired 85 number, have been centered in the sections formed by the reinforcing rods 13 concrete 17 is poured or tamped into the spaces between the opposing tile units, and over and around the reinforcing rods 13, thus creating 90 two systems, at right angles one to the other, of concrete ribs 17. In this process the concrete 17 forms a secure bond with the closed side walls of certain of the tiles in each unit, and with the end faces of the side walls and webs of certain others of the tiles in each unit. Furthermore, in the pouring and tamping of the concrete, the latter enters the open ends of the tiles as indicated in Fig. 4, and effects 95 a bond with the interior faces of the tile walls and webs within the cells of the tiles. The concrete thus entering the cells of the tiles finds its proper angle of repose, which in turn is determined in part by the frictional engagement of the concrete with the interior 100 walls and webs of the tiles. The concrete thus entering the cells of the tiles finds its proper angle of repose, which in turn is determined in part by the frictional engagement of the concrete with the interior 105 walls and webs of the tiles. With the proper mix and proper tamping the concrete will assume somewhat the position shown in Fig. 4, in which the concrete by reason of its frictional engagement with the upper face of the 110 cell is shown to have formed a shoulder 18, and by its frictional engagement with the lower wall of the cell, a shoulder 19 of greater extent. These protrusions of concrete into the cells are not only firmly bonded to the 115 cell walls on top, bottom and sides, but form elements which interlock with the tiles.

As shown in Fig. 2, the reinforcing bars 13, between the beams or girders 11, are positioned in the lower portion or chord of the concrete ribs 17, to act as tension members. At, and in the locality of, the beams or girders 11, the reinforcing bars 13, are deflected upward into the upper portion or chord of the ribs 17, again to act as tension members, in 125 accordance with well known mechanical principles. In Fig. 2, the reinforcing bars 13, instead of being continuous through the girders 11, at the lower portions of the ribs 17, are discontinued at and by reason of the I 130

beams 11, and other short reinforcing bars 21 are positioned in the concrete ribs 17 in the upper chord thereof from one to the other side of the I beams 11; this being the mechanical equivalent of the aforementioned upward and downward deflection of the reinforcing rods at the beams or girders 11. Between girders 11, the upper portions or chords of the concrete ribs 17 are in compression; and likewise the upper portions or chords of the tiles in their abutment and bearing, one on the other in each four-tile unit, and in their union and abutment with the concrete ribs 17, are in compression.

In the modified form of the invention shown in Figs. 3, 4, and 5, the four tiles which form each unit are otherwise arranged. In this form of the invention the tiles of the several units are so arranged that instead of having the open end of one tile abutting the side wall of an adjacent tile, the tiles are placed end to end with side wall to side wall so that, as respects each four-tile unit, there are open ends on two sides of the unit and closed faces on the other two sides of the unit. In such an arrangement the flow of the concrete into the quadruple tile unit is only from two of the adjacent concrete ribs 17; and the mechanical interlocking by reason of the concrete protrusions 20 is only with such two concrete ribs 17. As to the other two ribs 17 the natural bond of the concrete with the side walls of the tiles is relied upon for proper union of tile and concrete.

A top surfacing 22 of concrete over the tiles is often desirable. As shown in Figs. 7 and 8 this top surfacing 22 is unitary with the cross systems of concrete ribs 17, and is advantageously formed or laid in the laying of the ribs 17 themselves.

In addition, however, to the added strength of the slabs as a whole which this surfacing 21 provides, it has a further advantage and function. In the cutting and baking of the tiles, irregularities may be formed in the faces thereof, as indicated in an exaggerated manner at 23 in Fig. 8, so that the abutment of the tiles one on the other in the several units may not be continuous throughout the opposing faces of the tiles. When however, a surfacing 22 is spread or tamped over the tiles, the concrete of such surfacing, as indicated at 24 in Fig. 8, will enter into any such interstices 23, thereby filling the same and causing the tiles to be braced one on the other continuously over the opposing faces of the tiles. Within the scope of the invention, concrete 24 may be tamped into any interstices between opposing faces of tiles without there being a surfacing 22 over the tops of the tiles.

As shown in Fig. 6, the tiles may have their corners cut on lines 25, so that, when the tiles are set together, openings 26 are provided which extend the depth of the tile. The side walls 27 of the tiles terminate at these

cuts 25; and, when the openings 26 are filled with concrete, concrete cores 28 are provided which bond the end walls 27 of adjacent tiles, one to the other; thus making the walls of one tile in effect mechanically continuous with the walls of the adjacent tiles. As indicated in Fig. 7 these concrete cores or fillings 28 may be unitary with the top surfacing 22 of concrete.

In Fig. 9 a form of the invention is shown in which the I beams of Fig. 2 are absent, and in which T shaped concrete beams 29 are substituted for the steel beams 11. These concrete beams 29 may be reinforced by metal rods 30 forming tension members at the base thereof. Metal stirrups 31 are shown in Fig. 9 as extended vertically downward from the upper part of the beams 29, under and around the reinforcing members 30, and upward again to the upper portion of the beams 29. These stirrups are ordinarily used in this type of construction to take care of shear in excess of what the concrete section will sustain.

I claim:

1. A floor structure or slab comprising a system of re-inforced concrete ribs forming an open-work the apertures of which are closed by units of hollow tile bonded to the ribs in the formation of the latter by the pouring or tamping, and setting, of the concrete between and against the tile units; each such tile-unit being an assembly of like tiles set and abutting one with the other in the plane of the slab and acting with the concrete in cantilever formation, and certain of which are open-ended to the concrete, the concrete being interlocked with the tile units in the flowing or tamping of the concrete by protrusion of concrete into those open ends or cells of the tiles of each unit which abut the concrete ribs.

2. A floor structure or slab comprising a two-way system of re-inforced concrete ribs forming a net-work the apertures of which are closed by units of hollow tile bonded to the ribs in the formation of the latter by the pouring or tamping, and setting, of the concrete between and against the tile units; each such tile-unit consisting of four tiles so set one to the other in the plane of the slab that one open end of each tile abuts the side wall of another tile; the tiles acting with the concrete in cantilever formation, and the concrete being interlocked with the tile units in the flowing or tamping of the concrete by protrusion of concrete into those open ends or cells of the tiles of each unit which abut the concrete ribs.

3. A floor structure or slab comprising a system of re-inforced concrete ribs forming an open-work the apertures of which are closed by units of hollow tile bonded to the ribs in the formation of the latter by the pouring or tamping, and setting, of the con-

crete between and against the tile units; each such tile-unit consisting of a plurality of standard tiles set and abutting one with the other in the plane of the slab and acting with the concrete in cantilever formation.

5 4. A floor structure or slab comprising a system of re-inforced concrete ribs forming an open-work the apertures of which are closed by units of hollow tile bonded to the 10 ribs in the formation of the latter by the pouring or tamping, and setting, of the concrete between and against the tile units; each such tile-unit consisting of a plurality of standard tiles set endwise and laterally one to the other in the plane of the slab and acting with the concrete in cantilever formation.

15 5. A floor structure or slab comprising a system composed of metal tension rods set in concrete and forming an open rib-work the apertures of which are closed by units of hollow tile bonded to the concrete in the formation of the ribs by the pouring or tamping, and setting, of the concrete between and against the tile units, and around the tension 20 rods; each such tile-unit consisting of a plurality of standard tiles set one to the other in the plane of the slab and acting with the concrete in cantilever formation; the concrete being interlocked with the tile units in 25 the flowing or tamping of the concrete by protrusion of concrete into those open ends or cells of the tiles of each unit which abut the re-inforced concrete ribs.

30 6. A floor structure or slab comprising a two-way system of re-inforced concrete ribs forming an open-work the apertures of which are closed by units of hollow tile bonded to the ribs in the formation of the latter by the pouring or tamping, and setting, of the concrete between and against the tile units; 35 each such tile-unit consisting of tiles so set one to the other in the plane of the slab that one open end of each tile abuts the side wall of another tile; the tiles acting with the concrete in cantilever formation.

40 45 Signed at New York, in the county of New York, and State of New York, this 26th day of May, 1927.

THEODORE BARBATO.
